(57) **CLAIM**

The ornamental design for a razor handle, as shown and described.

DESCRIPTION

FIG. 1 is a bottom view of a razor handle;
FIG. 2 is a left, side view of the razor handle;
FIG. 3 is a top view of the razor handle;
FIG. 4 is a right, side view of the razor handle;
FIG. 5 is a front view of the razor handle;
FIG. 6 is a rear view of the razor handle;
FIG. 7 is a top, right, isometric view of the razor handle; and,
FIG. 8 is a top, right, isometric view of the razor handle,
depicting a razor cartridge as attached with the razor handle.
The broken lines in FIG. 5 illustrate portions of the razor
handle that form no part of the claimed design.
The broken line disclosure of a razor cartridge in FIG. 8
illustrates the environment and forms no part of the claimed
design.
